WITNESS:

E. I. Jeffries INVENTOR
BY *Victor J. Evans* ATTORNEY

UNITED STATES PATENT OFFICE

EWING IRVIN JEFFRIES, OF NEW SALEM, PENNSYLVANIA

PAGE-HOLDING DEVICE

Application filed April 12, 1927. Serial No. 183,134.

This invention relates to a page holding device for pads, books and the like, the general object of the invention being to provide a U-shaped member which is frictionally connected with a part which is adapted to be attached to the pad or book, said member, in one position, acting to hold the turned-up leaves of the pad against closing movement and in another position of the member 10 acting to hold the leaves in closed position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view showing the device in use on a pad as holding some of the leaves 25 thereof in open position.

Figure 2 is an elevation showing the clip and leaf holder of Figure 1.

Figure 3 is a view of the leaf holder.

Figure 4 is a view of the clip.

Figure 5 is a view of a plate adapted to be used in connection with a loose leaf holder.

As shown in these views, the page holder A is composed of a piece of wire or the like bent into U-shape with an offset 1 at the junction of the limb 2 with the bight 3. The limb 4 is curved slightly so that when this limb is placed in the barrel 5 of the pad engaging clip B, it will remain in place and it will also 35 act to engage the barrel with enough friction to hold the member A in adjusted position. Thus when the member A is moved to the position it occupies in Figure 1, it will remain in this position, due to the frictional engagement of the limb 4 in the barrel 5, and in this 40 position it will act to hold the leaves 6 of the pad 7 in open position. By swinging the member A downwardly upon the top of the pad, it will hold the leaves in closed position. By having one end of the device open,

the leaves can be readily passed under the limb 2. The offset portion 1 of the U-shaped member defines a pocket arranged to receive the adjacent edges of the pages or leaves of the book when they are arranged to occupy 55 the position illustrated in Figure 1, and thus prevent the pages or leaves from becoming casually separated from the U-shaped member under any circumstances.

Figure 5 shows a plate 8 which is formed 60 with a barrel 5' to receive the curved limb of the device A and this plate is also provided with the holes 9 for receiving the posts of a loose leaf holder so that the device can be used for holding the leaves attached to 65 the holder in open and closed position.

It is thought from the foregoing description that the advantages and novel features of my invention will be readily apparent.

I desire it to be understood that I may 70 make changes in the construction and in the combination and arrangement of the several parts, provided that such changes fall within the scope of the appended claims.

What I claim is:—

1. An attachment for a book comprising a substantially U-shaped clamp embracing one end of the book and pages thereof, the uppermost parallel portion being rolled upon itself to form a sleeve, a substantially 80 U-shaped clip formed from a single length of wire and having one limb curved longitudinally and adapted to be straightened when passed through said sleeve, whereby said clip is mounted for pivotal movement 85 but may be held fixed relatively with relation to the clamp in a given position, the other limb of said clip being extended transversely across and above said book for the purpose specified. 90

2. In combination with a member provided with leaves, a second member engaging a part of the said first member and having a part rolled upon itself to provide a sleeve, a U-shaped clip formed from a single 95 length of wire and having one limb received by the sleeve, whereby the clip is supported for pivotal movement to occupy either a horizontal or vertical position, the cross piece of said clip being offset at its point of 100

uncture with the other limb to define a pocket adapted to receive the adjacent edges of the leaves when the latter are opened with the clip arranged vertically.

- 5 3. In combination with a plurality of leaves bound together at one edge, guide means adjacent the bound edge, a member rotatably and reciprocably connected with said guide means to reciprocate in a direction parallel to the bound edge and to rotate in a plane at right angles thereto, said member having leaf engaging means adapted to be engaged with opened leaves by manipulation of the member to retain said leaves in open position, said member and means being capable of being disposed flatly overlying the leaves when the leaves are in closed position.
- 10 4. In combination with a plurality of leaves bound together at one edge, a guide mounted adjacent said bound edge and arranged parallel thereto, a member having an elongated portion rotatably and reciprocably mounted in said guide, the outer 15 end of said member being hooked whereby the member may be disposed flatly overlying the leaves or be extended and rotated to align the hook with opened leaves and then engaged with the leaves to retain them in open position.
- 20 25 30

In testimony whereof I affix my signature.
EWING IRVIN JEFFRIES.
